UNITED STATES PATENT OFFICE.

SIMON HEITER AND SALOMON J. LESEM, OF NEW YORK, N. Y.

DESIGN FOR AN UMBRELLA-HANDLE.

SPECIFICATION forming part of Design No. 11,687, dated March 16, 1880.

Application filed February 16, 1880. Term of patent 3½ years.

To all whom it may concern:

Be it known that we, SIMON HEITER and SALOMON J. LESEM, citizens of the United States, both residing at New York, in the county and State of New York, have invented and produced a new and original Design for Umbrella or Parasol Handles, of which the following is a specification, reference being had to the accompanying drawings, forming part thereof.

Our invention is designed to produce a new and original shape or configuration for umbrella or parasol handles.

Figure 1 of the accompanying drawings represents a side view of our newly-designed handle, and Fig. 2 a plan of the top ornament.

a is the handle, whose general contour is round and uniform throughout until near the upper part, where it gradually enlarges into a flattened club-shaped head, as seen at *b*, with an oblique cut, *c*, on one side.

d represents an ornamental disk of carved

work, of broadly elliptical form, having its upper and lower faces slightly convex, which surrounds the club-shaped head *b*, resting thereon in an angular or oblique direction.

The ornament *d* may be made of the same material as the other parts of the handle, or of some different material, such as will form a pleasing and striking contrast with the rest of the handle and increase the beauty of the design.

What we claim as new, and desire to secure by Letters Patent, is—

The design for an umbrella or parasol handle, consisting of the club-shaped head *b*, surrounded by the ornament *d*, as shown in the accompanying drawings.

SIMON HEITER.
SALOMON J. LESEM.
